US00D856288S

(12) **United States Design Patent** (10) **Patent No.:** **US D856,288 S**
Altonen et al. (45) **Date of Patent:** **** Aug. 13, 2019**

(54) **BUTTONS FOR A LOAD CONTROL DEVICE**(71) Applicant: **Lutron Technology Company LLC**,
Coopersburg, PA (US)(72) Inventors: **Gregory Altonen**, Easton, PA (US);
Jason C. Killo, Emmaus, PA (US);
Brad Michael Kreschollek, Bethlehem,
PA (US); **Noel Mayo**, Philadelphia, PA
(US)(73) Assignee: **Lutron Technology Company LLC**,
Coopersburg, PA (US)(**) Term: **15 Years**(21) Appl. No.: **29/645,226**(22) Filed: **Apr. 24, 2018****Related U.S. Application Data**(62) Division of application No. 29/586,663, filed on Dec.
6, 2016, now Pat. No. Des. 818,445.(51) **LOC (12) Cl.** ..... **14-03**(52) **U.S. Cl.**USPC ..... **D13/168**(58) **Field of Classification Search**

Primary Examiner — Selina Sikder(74) *Attorney, Agent, or Firm* — Philip Smith; Glen
Farbanish; Amy Yanek(57) **CLAIM**We claim the ornamental design for a buttons for a load
control device, as shown and described.**DESCRIPTION**FIG. 1 is a perspective view of buttons for a load control
device according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of buttons for a load control
device according to a second embodiment of our new
design; and,FIG. 8 is a front view thereof, the left side, right side, top,
and bottom views respectively, of the second embodiment
being identical to the left side, right side, top, and bottom
views of the second embodiment.The rear views form no part of the design and are omitted.
The broken lines showing portions of the remote control are
for the purpose of illustrating environmental structure and
form no part of the claimed design.**1 Claim, 6 Drawing Sheets**(58) **Field of Classification Search**
